UNITED STATES PATENT OFFICE.

JAMES P. WIGAL, OF HENDERSON, KENTUCKY, ASSIGNOR OF THREE-FOURTHS TO CHARLES E. SUGG, SAMUEL S. WATHEN, AND ROBERT B. CHEANEY, OF SAME PLACE.

MEANS FOR DISJOINTING PIPES.

SPECIFICATION forming part of Letters Patent No. 653,978, dated July 17, 1900.

Application filed April 14, 1900. Serial No. 12,836. (No model.)

To all whom it may concern:

Be it known that I, JAMES P. WIGAL, a citizen of the United States, and a resident of Henderson, in the county of Henderson and 5 State of Kentucky, have invented a new and Improved Means for Disjoining Pipes, of which the following is a full, clear, and exact description.

The invention relates to pipe-joints having 10 soft-metal rings as a packing.

The object of the invention is to provide a new and improved means for removing a solid ring of soft metal in the joint to allow of readily disconnecting the sections of the pipe-line without first disturbing or removing the pipe-line in the ditch or other support carrying 15 the pipe-line.

The invention consists of novel features and parts and combinations of the same, as 20 will be fully described hereinafter and then pointed out in the claim.

A practical embodiment of the invention is represented in the accompanying drawings, forming a part of this specification, in which 25 similar characters of reference indicate corresponding parts in both the views.

Figure 1 is a perspective view of the improvement, and Fig. 2 is an enlarged sectional side elevation of the same.

30 In disconnecting the sections of a pipe-line as heretofore practiced it was necessary to heat the joints of adjacent sections sufficiently to melt the soft-metal ring and to allow the molten metal to run out of the joint 35 before it was possible to remove one section from the other. In pipe-lines under ground it was necessary to first remove the line from the ground and then build a fire around the joint to melt the ring, and it not only required 40 a large amount of fuel, but it also took considerable time and labor to successfully accomplish the object.

With my method presently to be described in detail it is not necessary to first remove 45 the pipe-line from the ditch to the surface of the ground, as the soft-metal ring is removed from the joint in a comparatively-inexpensive manner and in a very short time.

The method consists, essentially, in sub-

jecting the soft-metal ring in the joint to the 50 action of a highly-heated running stream of molten metal to cause the ring to melt and run with the said applied stream of metal out of the joint, the whole amount of molten metal being saved and by additional heating 55 is in condition for similarly treating other joints in the pipe-line.

In order to carry this method into effect, I proceed as follows: A pot A, containing an easily-fusible metal—such as lead, for instance—is heated over a fire in a furnace or other apparatus until the metal is in a molten condition and highly heated, and then the pot, by the aid of a suitable carrying device B, is carried to the joint to be treated and 60 then the molten metal is poured through an inlet C' into an annular recess C², formed in a ring-shaped casing C, encircling the pipe-section D adjacent to the head D' of the other pipe-section D², the recess C² opening into 65 the face of the solid soft-metal packing-ring E in the joint of the two pipe-sections D D², as is plainly indicated in Fig. 2. The inlet C', leading to the recess C², is at the top of the casing C, and an outlet C³ leads from the 70 bottom of the recess and discharges the molten metal into a suitable receptacle F beneath the pipe-line, as indicated in Fig. 1. Now it is evident that the molten metal poured 75 into the recess comes in contact with the solid soft-metal ring and readily melts or fuses the same; and this additional molten metal of the ring mixes with the molten metal in the recess and flows with the same through the outlet C³ into the receptacle F. Pouring 80 metal from the pot A into the casing C is continued until the entire ring E in the joint has been melted and run out of the joint and 85 casing into the receptacle F. When this has been accomplished, one or both pipe-sections 90 can be readily moved lengthwise to completely disconnect the sections. It is understood that by the method described a stream of highly-heated molten metal is made use of and run in contact with the solid soft-metal 95 ring in the joint to cause the ring to melt and flow with the active molten metal out of the joint and the casing, as above described.

The casing C is preferably made in sections adapted to be fastened together by clamps or bolts after the sections are placed on the pipe.

Having thus fully described my invention, 5 I claim as new and desire to secure by Letters Patent—

The herein-described method for disjointing pipes and the like, consisting in subjecting the soft-metal ring in the joint to the action of a running stream of molten metal, to

cause the soft-metal ring to melt and run with the said running stream of molten metal, as set forth.

In testimony whereof I have signed my name to this specification in the presence of 15 two subscribing witnesses.

JAMES P. WIGAL.
